UNITED STATES PATENT OFFICE

FINN T. IRGENS, OF WAUWATOSA, WISCONSIN, ASSIGNOR TO OUTBOARD MOTORS CORPORATION, OF MILWAUKEE, WISCONSIN, A CORPORATION OF MICHIGAN

BREAKER MECHANISM

Application filed February 28, 1932. Serial No. 595,271.

This invention relates to improvements in breaker mechanism. It has particular reference to the mounting of such mechanism in a manner to avoid erratic effects sometimes attributable to the association of breaker mechanism with a wobbling shaft.

It is the primary object of the invention to provide breaker mechanism wherein those portions of the apparatus which are usually fixed may be provided with a special mounting which is arranged to take its position in accordance with the position of the shaft on which the breaker cam is mounted so that, notwithstanding any irregularity of shaft movement, the relatively fixed contact will always occupy the same predetermined relation to the axis of the shaft.

The invention has particular application to outboard motor organizations which are provided with starting motors assembled on the projected crank shaft at a point above the uppermost crank shaft bearing. In such structures there is a considerable length of crank shaft which is free to wobble above the bearing, and at high engine speeds the irregular movement of the free end of the shaft has been productive of extremely erratic timer action. By floating the fixed contacts of the breaker mechanism directly from the shaft, while nevertheless providing for the mounting of such parts independently of the shaft, I have succeeded in overcoming the difficulties heretofore experienced in providing a dependably operative timer.

In the drawing:

Figure 1 is a vertical axial section through the upper end of an outboard motor power head including a starting motor and breaker mechanism embodying this invention.

Figure 2 is a detail view of the breaker mechanism in plan.

Figure 3 is a fragmentary detail view in plan, showing a portion of the breaker mechanism cut away to expose the relatively movable contacts thereof.

Figure 4 is a detail view in side elevation of the parts shown in Fig. 2.

Like parts are identified by the same reference characters throughout the several views.

I have shown at 5 the crank case of an internal combustion engine to which this particular embodiment of the invention is applied. Fastened to the crank case is a motor housing 6 carrying the field magnet 55 7 for the starting motor. The motor armature 8 and commutator 9 are mounted on crank shaft 10. Their length is necessarily such as to extend the crank shaft for a substantial distance above its upper bearing 55 at 11.

The cam shaft 12 is conveniently mounted on the commutator in axial alignment with crank shaft 10. It may be slotted at 13 to receive a crank for emergency use. The 65 cover shell 14 connected with housing 6 has a removable cap at 15 to expose the cam shaft and breaker mechanism. The cam shaft has concentric portions 16 and 17 and an intermediate slightly flattened cam portion 18 as shown best in Figs. 1 and 3.

The breaker mechanism which co-operates with the cam shaft is mounted for unitary oscillation on a disk or plate 20 which is carried by bracket 21 and posts 22 from the 75 upper motor closure plate 23. A Bowden wire 24 may be connected to plate 20 for the timing adjustment thereof, as shown in Fig. 2.

The insulating blocks 25 which carry the 80 relatively fixed contacts 26 are mounted between upper and lower arms 27 and 28 which are unitarily movable as a lever upon fulcrum posts 29 which are carried by the timing disk 20. Each of the upper and lower arms 27 and 28 is provided with a socketed portion 32, and each socket carries a brush 33 of fiber or the like. The brushes 33 ride on the concentric portions 16 and 17 of the cam shaft extension 12 of the crank shaft, 85 thereby determining the radial distance of the fixed contacts 26 from the axis of the shaft, and maintaining such distance constant irrespective of any wobbling of the shaft which may occur due to its heavy 90 loading and the distance to which it projects above the bearing 11.

Tension springs 35 and 36 connected with the lever arms 27 and 28 respectively, as shown in Figs. 2, 3 and 4, hold the respec- 100

tive brushes 33 to the shaft and enable the fixed contact supports to follow all movements of the shaft which might otherwise affect the timing. In the course of any such 5 movements the lever arms oscillate about posts 29 through which desired timing movements are readily communicated to the relatively fixed contacts.

Pivoted by means of hub elements 37 from 10 posts 29 are the breaker levers 38, each of which has an arm carrying the relative movable contact 39 and another arm registering with the cam portion 18 of the cam shaft and provided with a socketed portion 40 15 carrying a cam follower brush 41. When the flattened cam portion 18 of the cam shaft registers with either of the cam follower brushes 41, it allows the movable contact 39 to engage fixed contact 16 as shown 20 in Fig. 3, thereby momentarily closing the electrical ignition circuit in the usual way. A tension spring at 43 holds the cam follower levers 38 and their respective cam follower brushes 41 to the cam 18.

25 Since both contacts take their relative positions from the shaft, it will be obvious that no wobbling or erratic movements of the shaft can in any way affect the relation of the contacts to each other. Thus, a regular 30 predetermined timing is assured.

I claim :

1. In a timer mechanism, the combination 35 with a cam shaft, a relatively fixed support, and breaker mechanism including relatively fixed and movable contacts, means yieldably mounting said relatively fixed contacts upon said support, means for governing the yielding movement of said relatively fixed contacts in accordance with erratic 40 movements of said shell, and means for actuating the relatively movable contacts from said shaft whereby the several contacts are positioned as to timing by said support and are positioned entirely by said 45 shaft in their movement to and from each other.

2. In a timer mechanism, the combination 50 with a timer shaft having a portion concentric with its axis, of a support movable for timing and mounted independently of said shaft, a lever pivoted to said support and provided with means bearing against the concentric portion of said crank shaft, a relatively fixed breaker contact carried 55 by said lever, a second contact movable with respect to said relatively fixed contact, and means for actuating said movable contact from said shaft.

3. In a timer mechanism, the combination 60 with a cam shaft provided with portions respectively concentric and eccentric with respect to its axis, of a pair of levers provided with means engaging the respective portions of said shaft, springs holding said 65 lever carried means to said shaft, and con-

tacts carried by the respective levers and movable relatively to each other solely in accordance with the variation in form between the eccentric and concentric portions of said shaft.

4. In a timer mechanism, the combination 70 with a cam shaft having portions respectively concentric and eccentric with reference to the axis of the shaft, of a timing support mounted independently of said shaft and movable angularly, a fulcrum post upon said support, upper and lower levers provided with means engaging the relatively concentric portions of the shaft and fulcrummed to said post, springs pressing said 75 means to said shaft, a relatively fixed contact carried by said levers and an intermediate lever provided with a spring, and cam follower means engaging the eccentric portion of the shaft and having a relatively 80 movable contact operable to and from engagement with said first mentioned contact in accordance with the eccentricity of said shaft portion.

5. In a timer mechanism, the combination 85 with a cam shaft having portions respectively concentric and eccentric with reference to its axis, of a movable timer support provided with fulcrum means, levers pivoted on said fulcrum means and disposed at opposite sides of the shaft, spring means connecting said levers, shaft engaging means carried by said levers and engaging the relative concentric portions of the shaft to determine the positions of said levers with respect to the shaft despite erratic movements thereof, relatively fixed contacts carried by said levers, and cam follower levers provided with relatively movable contacts and with cam follower means engaging the relatively 90 eccentric portions of the shaft to receive motion therefrom.

6. The combination with a cam shaft having upper and lower portions concentric with its axis, and an intermediate portion concentric with reference thereto, of a plate oscillatable about the axis of said shaft for timing and provided with an independent mounting permitting such oscillation, fulcrum posts carried by said plate, upper and lower lever arms mounted on said posts at opposite sides of said shaft and provided with means engaging the relatively concentric portions of the shaft, springs connecting opposite arms whereby to maintain said means in contact with said shaft, intermediate lever arms mounted on said posts between said first mentioned lever arms and provided with means engaging the relatively eccentric portion of the shaft, spring means connecting said intermediate lever arms, and electrical contacts carried by the arms respectively positioned by the eccentric and concentric portions of said shaft whereby to occasion movement of said con- 100 105 110 115 120 125 130

tacts with reference to each other, both of said contacts taking their relative positions in a radial direction entirely from said shaft and in a timing direction entirely from said support.

7. The combination with a shaft extended above its uppermost bearing, of a cam shaft extension including portions relatively concentric and eccentric with reference to the axis 10 of said cam shaft extension, levers provided with shaft engaging means respectively associated with the concentric and eccentric portions of said cam shaft extension, and contacts carried by the respective levers and 15 movable to and from engagement with each other in accordance with the variation in form between said shaft portions, both of said contacts taking their position of radial adjustment directly from said shaft whereby 20 to be unaffected by erratic movements thereof.
